UNITED STATES PATENT OFFICE.

VERNON ROYLE, OF PATERSON, NEW JERSEY.

SHUTTLE FOR SEWING-MACHINES.

SPECIFICATION forming part of Letters Patent No. 690,616, dated January 7, 1902.

Original application filed September 15, 1897, Serial No. 651,748. Divided and this application filed October 25, 1901.
Serial No. 79,916. (No model.)

To all whom it may concern.

Be it known that I, VERNON ROYLE, a citizen of the United States, and a resident of Paterson, in the county of Passaic and State 5 of New Jersey, have invented a new and useful Shuttle, of which the following is a specification.

My invention relates to shuttles, with the object in view of providing a shuttle which 10 will admit of an inspection of the cop of thread within it without opening the shuttle and in which the tension device is located on the exterior of the end of the shuttle out of the way of the cop of cord or thread within 15 the shuttle.

My present application is a division of my pending application, Serial No. 651,748, filed September 15, 1897, entitled "Machine for lacing jacquard-cards."

20 In the accompanying drawings, Figure 1 is a view of the shuttle in side elevation. Fig. 2 is a longitudinal section showing the position of the cop therein. Fig. 3 is a view of the rear end of the shuttle, and Fig. 4 is a transverse section in the plane of the line A A of Fig. 1.

The body of the shuttle is denoted by *a* and is made skeleton in form, being provided on each of four sides with an elongated opening *b*. The rear lining *c*, of some thin material—such, for example, as sheet-brass—is inserted within the shuttle to receive the cop of cord or thread, and the said lining is cut away opposite one or more of the openings *b*, (in the 35 present instance opposite the opening on the outer side of the shuttle or that side opposite the side wall of the raceway,) and a film *d*, of some suitable transparent or translucent material—such, for instance, as celluloid—is placed in the opening and serves to admit of an examination of the condition of the cop within the shuttle whenever the operator glances in that direction and at the same time 40 protects the cop from dust and foreign substances. By this means the operator can determine at a glance when the cop is nearly exhausted and so determine the time when a new cop should be inserted before the end of

the previous cop is left too short to make a good connection. 50

The rear end of the shuttle *a* is provided with a cap *e*, which cap is in the present instance hinged to the body portion of the shuttle and retained in its closed position by a spring-catch *f*. (See Fig. 3.) 55

The outer face of the cap *e* is preferably dished, as shown at *g*, (see Fig. 2,) and within this dished portion the tension-spring *h* is located.

The cord *i* from the cop within the shuttle 60 is led from the crown of the cap *e* at the rear end of the shuttle and thence beneath the tension device and along to the guide *j*, as shown in Figs. 1, 2, and 3. This serves to draw the cord directly from the interior of 65 the cop without causing it to bind across the end of the cop, and hence causes the cop to unwind naturally and without any liability of becoming snarled. It also serves to locate the tension device entirely out of the way of 70 the bearing-surface of the movable parts and out of the way of the cop within the shuttle and admits of constructing the cop with smooth unobstructed exterior side walls and with a smooth and unobstructed interior. 75

What I claim is—

1. A shuttle provided with one or more peep-holes through its wall and a transparent film covering the said peep hole or holes, substantially as set forth. 80

2. A shuttle comprising a body portion and a cap at its end for closing and opening access to the interior of the shuttle, the said cap being provided with a cord-discharge opening therethrough and with a tension device 85 located on the exterior of the cap, substantially as set forth.

In testimony that I claim the foregoing as my invention I have signed my name, in presence of two witnesses, this 16th day of October, A. D. 1901. 90

VERNON ROYLE.
